UNITED STATES PATENT OFFICE.

FRANKLIN W. KREMER, OF CARLSTADT, NEW JERSEY.

CIRCULAR CALENDER-CUTTER.

1,130,909.

Specification of Letters Patent.

Patented Mar. 9, 1915.

Application filed May 21, 1912. Serial No. 698,790.

To all whom it may concern:

Be it known that I, FRANKLIN W. KREMER, a citizen of the United States, residing at Carlstadt, in the county of Bergen and State 5 of New Jersey, have invented a new and useful Circular Calender-Cutter, of which the following is a specification.

One object of the present invention is to provide a knife so supported and constructed 10 that it may be employed for cutting a web upon a roller, without endangering the web through the tearing or dragging action of the knife.

A further object of the invention is to 15 provide means whereby the knife may be supported yieldably, to coöperate with the web which is upon the roll.

The invention aims to provide novel means 20 whereby the knife may be adjusted longitudinally of the roll and transversely of the roll.

With the foregoing and other objects in 25 view, which will appear as the description proceeds, the invention resides in the combination and arrangement of parts and in the details of construction hereinafter described and claimed, it being understood that changes 30 in the precise embodiment of invention herein disclosed can be made within the scope of what is claimed without departing from the spirit of the invention.

In the drawings,—Figure 1 shows the invention in end elevation; Fig. 2 is a vertical transverse section upon the line 2—2 of Fig. 35 1; Fig. 3 is a side elevation of the knife-supporting structure; Fig. 4 is an elevation of the structure shown in Fig. 3, the view point in Fig. 4 being 90° remote from the view point in Fig. 3; and Fig. 5 is a fragmental 40 elevation showing a modified detail of the invention.

In the accompanying drawings, the numeral 1 indicates a supporting frame which 45 may be of any form. In the present instance, the frame 1 is disclosed as comprising spaced standards 2 in which calender rolls 3 and 4 are adjustably supported. The batch 5, which is ordinarily a rubber compound, is placed against the calender rolls 50 3 and thereby is fashioned into a web 6 which may be wound upon a mandrel 7 supported by a shaft 8, the shaft 8 being ordinarily carried by the frame 1. As the web 6 is wound upon the mandrel 7, a web 9 is 55 introduced between the convolutions of the web 6, for the purpose of preventing the

convolutions of the web 6 from adhering, the web 9 being ordinarily textile material. The web 9 is carried in the form of a roll, upon a shaft 10 which may be journaled for 60 rotation upon a frame 11.

The invention further includes a knife support 12, ordinarily taking the form of a shaft journaled in the frame 1. The shaft 12 is equipped with a lever 14, coöoperating 65 with a frame-supported segment 15 having a slot 16 adapted to receive a set screw 17 which is threaded into the lever 14. By means of the lever 14, the shaft 12 may be rotated, the shaft being held at any desired 70 position by manipulating the screw 17 so that the same binds against the segment 16; although any known means may be employed for limiting the movement of the lever.

A plurality of knife carriers are mounted 75 upon the knife support 12, for movement longitudinally of the rolls 3, the knife carriers being connected with the knife support in such a manner that when the knife support is rotated, the carriers will be rotated. 80 Each carrier preferably takes the form of a collar 18 provided with a groove 19 receiving a spline 20 which is fashioned upon the knife support or shaft 12. The collar 18 is equipped with projecting lugs 21 carrying a 85 pivot element 22 upon which is fulcrumed a knife holder 23, preferably taking the form of a bar. Each collar or knife-carrier 18 is supplied with a lug 24 through which passes a pin 25 connected by means of a pivot element 26 with one end of the knife holder 23. Upon the free end of the pin 25 may be mounted washers 27 between which is interposed a compression spring 28, the extremity of the pin 25 being threaded as shown at 29 90 to receive a nut 30, of any form, the nut bearing against one of the washers 27. The collar or knife-carrier 18 is provided at one side with a boss 31 into which is threaded a set screw 32, adapted to engage the shaft 12. 100 By loosening the set screw 32, the collar 18 may be slid longitudinally of the shaft 12, relative rotatory movement between the shaft 12 and the collar 18 being prevented by the spline construction 19—20. 105

Adjacent its free end, the knife holder 23 may be bifurcated to form spaced arms 33, receiving a shaft 34, upon which is carried a rotary knife 35, formed at its periphery with a cutting edge 36. If desired, the knife holder may be modified to the extent indicated at 37 in Fig. 5, the holder 37 being 110

equipped with arms 38, spaced apart more widely than the arms 33, a shaft 39 being carried by the arms 38, a plurality of rotary knives 40 being supported upon the shaft 39, 5 and washers 41 being interposed between the knives 40 and between the knives and the arms 38.

In practical operation, the shaft or knife support 12 is rotated through the medium 10 of the lever 14 until the knives 35 bear yieldingly against the web 6 as the same traverses one of the calender rolls 3. The spring 28 is thus put under tension, and the knife 35 is yieldingly held against the web. Owing to the yielding support furnished by the spring 28, and owing to the fact that the knife 35 is mounted for rotation, the knife will sever the web without causing a tearing or stripping thereof, should an obstacle in 15 the web be encountered by the knife. As will be understood, the knife 35 may be held at any desired adjustment with respect to the calender roll 3, through the medium of the set screw 17. By loosening the set 20 screws 32, the several knife-carriers 18 may be spaced at the required distances apart, the spline mechanism 19-20 serving to hold the knife-carriers 18 upon the shaft 12 for rotation therewith.

30 It is desirable at times to sever the web 6 into strips of but slight width, and to accomplish this result, the double knife construction shown in Fig. 5 may be employed.

Having thus described the invention, 35 what is claimed is:—

1. In a device of the class described, a roll; means for supporting the roll; a rotary knife; and means for adjusting the knife in a fixed straight line longitudinally of the 40 roll, and transversely of the roll.

2. In a device of the class described, a roll; means for supporting the roll; a rotary knife; means for adjusting the knife longitudinally of the roll; means for adjusting 45 the knife transversely of the roll; and yieldable means, independent of the last specified adjusting means, for limiting the movement of the knife transversely of the axis of the roll.

50 3. In a device of the class described, a roll; means for supporting the roll; a knife support; and a rotary knife adjustable along the support only in the direction of the length of the roll and cooperating with the roll.

60 4. In a device of the class described, a roll; means for supporting the roll; a knife support rotatably mounted adjacent the roll; a rotary knife adjustable along the support only in the direction of the length of the roll; and means for rotating the support to move the knife transversely of the roll.

65 5. In a device of the class described, a roll; means for supporting the roll; a knife

support mounted for rotation adjacent the roll; a rotary knife adjustable along the support only in the direction of the length of the roll; means for rotating the support to move the knife transversely of the roll; and independent, resilient means for limiting the movement of the knife transversely of the axis of the roll.

6. In a device of the class described, a roll; means for supporting the roll; a knife support mounted for rotation adjacent the roll; a knife carrier movable upon the support, longitudinally only of the roll; means for securing the knife carrier to the support; and means for rotating the support to 80 adjust the carrier transversely of the roll.

7. In a device of the class described, a roll; means for supporting the roll; a knife support mounted for rotation adjacent the roll; a knife carrier movable upon the support longitudinally only of the roll; interengaging elements upon the carrier and upon the support for preventing relative rotatory movement only between the carrier and the support; and means for rotating the support to 90 adjust the carrier transversely of the roll.

8. In a device of the class described, a roll; means for supporting the roll; a knife support journaled for rotation adjacent the roll; a knife-carrier movable upon the knife support longitudinally only of the roll; interengaging elements upon the knife carrier and upon the support for preventing relative rotatory movement only between the carrier and the support; means independent of the interengaging elements for retaining the carrier upon the support against movement longitudinally of the support; and means for rotating the support to 100 adjust the position of the carrier transversely of the roll.

9. In a device of the class described, a roll; means for supporting the roll; a knife support located adjacent the roll; a knife carrier movable upon the support, longitudinally of the roll; a knife holder pivotally connected with the carrier; and spring means operatively connected with the holder and with the carrier to move the 110 holder transversely of the axis of the roll.

10. In a device of the class described, a roll; means for supporting the roll; a knife support journaled for rotation adjacent the roll; a knife carrier movable longitudinally only of the support; a knife holder pivotally connected with the carrier; spring means operatively connected with the holder and the carrier for moving the holder transversely of the axis of the roll; interengaging elements upon the support and upon the carrier for preventing relative rotatory movement between the carrier and the support; and means for rotating the support to 125 adjust the holder transversely of the roll.

11. In a device of the class described, a roll; means for supporting the roll; a knife support journaled for rotation adjacent the roll; a knife carrier adjustable upon the support longitudinally only of the roll; interengaging elements upon the carrier and upon the support for preventing relative rotatory movement only between the carrier and the support; means independent of the 5 interengaging elements for maintaining the carrier against movement longitudinally of the support; a knife holder pivoted to the carrier; spring means operatively connecting the holder and the carrier for moving 10 the carrier transversely of the axis of the roll; a knife mounted upon the holder; and means for rotating the support.

12. In a device of the class described, a roll; means for supporting the roll; a knife support journaled for rotation adjacent the 20 roll; a knife carrier adjustable longitudinally only of the support and held upon the support for rotation therewith; a knife supported by the carrier; means for rotating the support to move the knife transversely 25 of the roll; and means for locking the support in successive positions.

In testimony that I claim the foregoing as my own, I have hereto affixed my signature in the presence of two witnesses.

FRANKLIN W. KREMER.
